GEORGE W. BISHOP

BY *Benj. T. Rauber*
This ATTORNEY.

UNITED STATES PATENT OFFICE.

GEORGE W. BISHOP, OF NEW YORK, N. Y.

GAME APPARATUS.

Application filed April 17, 1922. Serial No. 553,637.

To all whom it may concern:

Be it known that I, GEORGE W. BISHOP, a citizen of the United States, residing at New York, in the county of Bronx and State of New York, have invented certain new and useful Improvements in Game Apparatus, of which the following is a specification.

This invention relates to a game apparatus and particularly to a football game apparatus suitable for indoor or parlor use in which the plays and the problems of strategy and tactics frequently met in actual football games are reproduced.

In football games the playing of the game is divided into periods of time which, to some extent influence the score which may be attained and the tactics to be used for contemplated plays. In game apparatus heretofore used this element of time has not been represented and many of the situations which call for the exercise of judgement in the selection of a play to be attempted have been lacking from these types of game apparatus, as, for example, the necessity of making a definite number of yards gain in a limited number of "downs," or the desirability of selecting a play which, if successful, will score within the time or number of plays which remain before the close of the game. Many of the more interesting features of the game are therefore lacking in game apparatus in which the time element is not represented and, moreover, this type of game fails to develop an understanding of the rules and fundamentals of the game.

An object of the present invention is to provide a game apparatus in which the more important problems of strategy and tactics encountered in actual football games are reproduced and in which the fundamental rules of the game are used and followed.

Another object of the invention is to provide a game apparatus in which the element of time is represented as well as the distance between goals.

A further object of the invention is to provide a field of play for football game apparatus of the above type in which both the distances between goals and the time of plays are graphically represented.

Still further objects of the invention are to provide a game apparatus in which a type of play may be selected and in which the chances for success or gain or for loss are

similar to those in actual games, and an apparatus in which the game may be governed by the official football rules.

With these and other objects in view, the invention comprises the apparatus described and set forth in the following specification and claims.

The various features of the invention are illustrated in the accompanying drawings, in which:

Fig. 1 is a plan view of a foot ball field forming a part of a preferred embodiment of the invention.

Fig. 2 is a view of a chart of plays to be used in connection with the field shown in Fig. 1.

Fig. 3 is a figure of a die having suitable numerals to indicate the value of the play and adapted to serve as an indicating means to determine the success of a play.

Fig. 4 is a top view of a marking device adapted to indicate the position of the ball on the field illustrated in Fig. 1.

Fig. 5 is a side view of the marking device shown in Fig. 4, and,

Fig. 6 is a view of a flag device to indicate the distance to be gained in a definite number of plays.

In the present invention the field of play is divided by a number of spaced transverse lines into spaces extending the length of the field, each space representing a definite number of yards on the field, and by lengthwise lines into a number of spaces extending across the field, each line or space representing a play. The play, or time, spaces or lines are preferably also separated into periods corresponding to the fifteen minute "quarters" of the usual football game. A marking device is provided which is adapted to be placed on the field at the intersections of the play spaces and length or distance lines, the position of the marking device on the distance lines indicating the progress of a player toward goal and its position on the play or time spaces indicating the number of plays used and those remaining before the end of the game, thus corresponding to the time used in an actual game.

The space gained or lost on each play is indicated by an appropriate number or other suitable indicating mark on a determining device such as a die or dice, a top or a spinner, the indication being purely the result of chance. The player may, how-

ever, determine in advance of his play the type of play he wishes to make and the number given by the dice or determining device indicates a gain or loss in accordance 5 with the type of play selected. A chart of plays is also provided which indicates the loss or gain for each type of play. Flag devices are also provided and adapted to be placed at the intersections of the play 10 spaces and distance lines to indicate the distance which must be gained and the number of plays in which the gain must be made.

Referring more particularly to the accompanying drawings, the distance between 15 goal lines 12 and 14 of a football field 16, shown on a reduced scale in Fig. 1, is divided into a number of spaces or zones 18 by a number of transverse lines 20, each space or zone representing a definite number 20 of yards. In the example illustrated in the drawings each space corresponds to a distance of five yards, the two yard distances being represented by short marks or dashes 22 to distinguish them from the five yard 25 lines. A center line 24 is also provided and end zones 26 and 28 are provided behind the opposite goal lines. The distance of each five yard line from its goal is indicated by numerals at the side of the field.

30 The width of the field does not correspond to the width of an actual football field but represents time, or a definite number of plays corresponding to definite time intervals. The width of the field is, therefore, divided into periods or quarters by means of longitudinal lines 32 extending the length of the field and each quarter is further divided by lines 34 into plays, each play corresponding roughly to about one 40 minute of time.

The progress of the game is marked by the 45 position of a marker 36 on the longitudinal and crosswise lines of the field. This marker is illustrated on a larger scale in Figs. 4 and 5 and may consist of a disc of leather, cardboard or other suitable material, preferably shaped to represent a football and having its opposite sides colored differently so that the possession of the ball may be indicated by the side which is uppermost. The marker may be arranged to lie loosely 50 on the field with its center at the intersection of the lines which indicate its position on the field.

55 The distance gained by either side is governed partly by the type of play selected by the player as, for example, a run, kick or forward pass, and partly by an indicator such as the die shown in Fig. 3, or other 60 indicating device, the value of whose indications is governed by chance. The player having possession of the ball or the offensive position states which type of play he selects and then throws the die to determine the extent of his gain or loss. A chart of

plays 38, Fig. 2, gives the value of each number of the die 37. At each play, therefore the player having the offense may select a type of play, throw the die and move the ball the distance indicated in the 70 chart for the play selected and the number given by the throw of the die. When certain numbers occur the ball is lost and the other player takes the offensive and continues to select the plays and cast the die 75 until he losses the ball. With each play, however, the ball is moved across the field one space whether it is lost to the opposing player or fails to gain or gains a definite number of yards. When the ball 80 reaches the side of the field the game is ended, this situation being analogous to the end of the time limit in the usual football game.

As in the usual football game, if a player 85 fails to make an advance of ten yards in four consecutive completed plays or downs, possession of the ball goes to the opposing player or side. The distance to be gained is indicated in the present game device by 90 flags 42, Fig. 6, having a pointed standard or pin 44 which may be stuck at the intersection of a crosswise distance line corresponding to an advance of ten yards and a lengthwise play or time line four spaces 95 in advance. If the ball does not cross the distance line before crossing the play line it is lost to the opposing side. In this play as in all of the other plays the official football rules are followed, the game permitting 100 the plays to be adapted to slight changes in the rules.

As an example of the manner of playing the game, goals are determined and the kick-off determined by toss. The side having the kick-off then places the ball on his forty yard line and throws the die. In this play the numbers "1" and "6" do not count, the throw being repeated if either of these numbers occur. If any of the other numbers occur the ball is moved forward a corresponding number of spaces, for example, forty yards for the number "4". The opposing player then throws the die and if the number "2" occurs the ball 115 is again kicked off, or if number "1" occurs the possession of the ball changes. If any of the other numbers occur the player moves the ball a corresponding distance towards his opponent's goal and moves the ball one 120 space across the field, this combined play of the two players constituting one play. This player, having possession of the ball, continues to select the type of play and throw the die, moving the ball one space across the field and the indicated number of yards lengthwise of the field until he reaches the goal or one of the side lines or loses the ball by rolling the numeral "6" on the die.

The range of gains and losses by the 130

different plays is chosen to correspond to those usually obtaining in the usual course of an actual game, the gains made by a run being much smaller than those made by the same numerals for a kick or forward pass and the ground which may be lost to the opponent in a run back are correspondingly smaller. On the other hand there is less likelihood of a forward pass being successful as the player must get one of two numerals, as "4" or "5" in the chart illustrated in Fig. 2, while any one of four numbers, "2", "3", "4" or "5" will give a measure of success in the run or kick plays. A "touchdown," however, requires that the ball be put over the opponent's goal on a run or forward pass, so that, where there is a chance of obtaining a touchdown, a run will be selected as the play rather than a kick play which would score as a, "goal from field," which counts three points as against the touchdown's six points. On each "first down" the flags are fixed on the distance line showing the distance to be gained in four "downs" and on the fourth time or play line in advance.

Each situation occurring in the present game corresponds to a corresponding situation in an actual football game and is governed by the same rules. The tactics to be used, are, therefore, similar to those required in an actual game, except such as develop from the ability of individual players, or from such considerations as nearness to the side lines and other minor factors which can not be duplicated in a game apparatus of this type. The playing of the present game not only provides amusement but also incidentally develops a knowledge of the rules of the game and of the reasons back of the different plays.

It will be understood that the rules for the present game apparatus may be changed to correspond with changes in the official rules and that minor changes in the manner of playing the game and in the form of the various elements of the apparatus may be made. The field of play may be printed or otherwise applied to a fabric, paper, board or other suitable medium. It will be understood that two dice may be used and the chart of play revised so that the chances of obtaining any definite number will be about the same as the chance of being successful in the corresponding play in an actual game.

Having described the invention, what I claim and desire to secure by Letters Patent is:

1. A game apparatus which comprises a field of play having spaced lines arranged to represent distances between goals, marks to indicate the distances of said lines from said goals, spaced lines at an angle to said

distance lines, to represent time intervals, marks to indicate the time intervals of successive lines from a starting line and a marker adapted to be placed on said field to indicate the progress of the game as to time and distance. 70

2. A game apparatus which comprises a field of play having lines spaced in one direction to represent distances between goals and lines transverse to said lines and spaced to represent play intervals, and a marker adapted to be placed on said field to indicate the progress of the game as to time and distance. 75

3. A game apparatus which comprises a field of play having spaced lines to indicate distance intervals between goals and spaced lines transverse to said distance interval lines to indicate intervals of play, a marker adapted to be placed at the intersection of said lines to indicate the progress of the game as to distance and play intervals, an indicating device adapted to present a series of numbers or values and a chart having represented thereon numbers to indicate the value of the numbers of said indicating device for different types of plays. 80 85 90

4. A game apparatus which comprises a field of play having spaced lines arranged to represent distances between goals, marks to indicate the distances of said lines from said goals, spaced lines at an angle to said distance lines, to represent time intervals and marks to indicate the time intervals of successive lines from a starting line. 95 100

5. A game apparatus which comprises a field of play having spaced lines to represent distances and spaced lines transverse to said lines to indicate play intervals, a marking device adapted to be positioned on said field at the intersections of said lines to indicate position, and a flag device adapted to be mounted on said field to indicate the distance to be gained in a definite number of plays. 105 110

6. A game apparatus which comprises a field of play having spaced lines to graphically represent distances between goals and spaced lines at an angle to said distance lines to indicate a limited number of plays, a marking device adapted to indicate position, a chart of plays showing different distances for different types of plays at different numbers and an indicating device adapted to indicate a play number by chance. 115 120

7. A game apparatus which comprises a field of play having spaced lines to graphically represent distances between goals and spaced lines at an angle to said distance lines to indicate a limited number of plays, a marking device adapted to indicate position, a chart of plays showing different distances for different types of plays at different numbers, an indicating device adapted to indicate a play number by chance and 130

a flag device adapted to be placed on said field to indicate the distance to be gained in a given number of plays.

8. A game apparatus which comprises a field of play having transverse goal lines near its opposite ends, a center line between said goal lines and a number of spaced distance lines between said center line and said goal lines, spaced play lines extending lengthwise of said field between said goal lines and adapted to indicate a definite number of plays, said plays being divided into periods, a marking device adapted to indicate a position on said play and distance lines, a chart of plays arranged to indicate a number of different types of plays and a series of numerals for each type and a definite distance value for each number and type, and an indicating device for indicating one number by chance.

9. A game apparatus which comprises a field of play having transverse goal lines near its opposite ends, a center line between

said goal lines and a number of spaced distance lines between said center line and said goal lines, spaced play lines extending lengthwise of said field between said goal lines and adapted to indicate a definite number of plays, said plays being divided into periods, a marking device adapted to indicate a position on said play and distance lines, a chart of plays arranged to indicate a number of different types of plays and a series of numerals for each type and a definite distance value for each number and type, and an indicating device for indicating one number by chance.

In testimony whereof I affix my signature.

GEORGE W. BISHOP.
